UNITED STATES PATENT OFFICE

103,137

DESIGN FOR A CASE OR SIMILAR ARTICLE

Walfrid Wallenthin, Attleboro, Mass.

Application June 11, 1936, Serial No. 63,240

Term of patent 14 years

To all whom it may concern:

Be it known that Walfrid Wallenthin, a citizen of the United States, residing at Attleboro, in the county of Bristol and State of Massachusetts, has invented a new, original, and ornamental Design for a Case or Similar Article, of which the following is a specification, reference being had to the accompanying drawing, forming a part thereof.

Fig. 1 is a perspective view of a case or similar article showing my new design.

Fig. 2 is a plan view thereof in open position.

Fig. 3 is a cross sectional view taken along line 3—3 of Fig. 1.

I claim:

The ornamental design for a case or similar article substantially as shown.

WALFRID WALLENTHIN.
